UNITED STATES PATENT OFFICE.

JOSEPH BLAZEK, OF CHICAGO, ILLINOIS.

REFRIGERATING SYSTEM.

Application filed September 15, 1924. Serial No. 737,642.

To all whom it may concern:

Be it known that I, JOSEPH BLAZEK, a citizen of the United States, residing at Chicago, in the county of Cook and State 5 of Illinois, have invented certain new and useful Improvements in Refrigerating Systems, of which the following is a specification.

This invention, in the form shown, is directed to refrigerated display counters, although the refrigerating system employed may be used under a variety of conditions, so that it will be understood that the specific details of construction herein set forth 10 are not, in the absence of express limitation, to be understood as imposing limitations on the use of the invention. The refrigerating system employed is one which utilizes jets of cold brine or other refrigerating medium 15 for the purpose of cooling the air within the compartment wherein perishable articles are stored, and for the purpose of establishing air currents which will tend to withdraw the warmer air from the upper 20 portions of the chamber or compartment, and, after cooling the same, recirculate the air back to the starting point. This system of cooling is peculiarly adapted for use 25 in the construction of refrigerated display counters, in that it permits the use of the entire upper portion of the counter for display purposes, and obviates the necessity 30 for providing ice chambers, or the like, which will interfere with the display of 35 goods and are otherwise objectionable, since they frequently interfere with easy access to the goods on display.

In the present invention, the brine tank and pump may be located in the lower portion 40 of the counter within space which is not desirable for the display of goods, so that the upper portion of the counter may, if desired, be walled in with glass and permit a ready inspection of the goods from 45 a point close to the eye of the observer.

Further objects and details of the invention will appear from a detailed description of the invention, which consists in the features of construction and combinations of 50 parts hereinafter described and claimed.

In the drawings:

Figure 1 is a longitudinal sectional view 55 of a refrigerated display counter embodying the features of the present invention and taken on line 1—1 of Fig. 2, being broken

away in the center to reduce the space occupied by the figure;

Fig. 2 is a cross sectional elevation of the same; and

Figs. 3, 4 and 5 are diagrams showing variations in the method of directing the spray into the chamber to be cooled.

As applied to a display counter, the invention comprises a brine tank 10 which occupies the lower portion of the counter 60 structure. The counter, as shown, comprises a front wall 11, a rear wall 12, a bottom or base 13, and end walls 14, all of the walls shown being of the insulated character 65 commonly employed in the construction 70 of refrigerators, ice boxes, and the like.

Above the brine tank chamber is a partition wall 15 which, as shown, slopes slightly from front to rear and is covered 75 on the top by metallic lining 16 and having near its rear edge one or more drain spouts 17 adapted to permit the cooling liquid to drain back into the underlying brine tank. Above the partition wall 15 is located a display shelf 18 which may be 80 formed of opalite glass or other convenient and sanitary material upon which to place the goods to be displayed.

The upper part of the display counter, as 85 shown, comprises a glass front wall 19, a top plate 20, and sliding doors 21 at the rear of the display portion of the counter which afford access to the interior thereof. It will be understood that the details of 90 construction of the display counter can be modified as desired without departing from the spirit of the invention.

Within the lower portion of the counter, as shown, is located a pump 22 immediately 95 adjacent to one end of the brine tank and opening thereto through a port 23. The pump is preferably driven by a motor 24 and serves to deliver cooling fluid under pressure through a header pipe 25 which, as 100 shown in Fig. 1, leads up to a point above the partition wall 15 and extends from end to end of the display chamber near the front thereof and at a point immediately beneath the front edge of the shelf 18. The header pipe is provided at suitable intervals with 105 openings or nozzles 26 which are preferably slightly elevated to direct jets of liquid across the space beneath the shelf 18 and in close proximity thereto.

It will be noted that the shelf is so ar- 110

ranged as to provide open slots or spaces 27 and 28 along the front and rear edges thereof which provide for the circulation of air from the storage space above the shelf to the cooling space beneath, and the flow of currents will be induced by the action of the spray jets, which not only serve to cool the air with which they come in contact, but also serve to maintain a current flow in the direction of movement of the emitted spray.

In order to provide for the coupling together of a series of counters to be served from the same brine tank, a second header pipe 29 is provided which leads from the pump 23 through the brine tank chamber and the opposite end wall 15, which header pipe is provided with a suitable coupling 30 to make connection with the next succeeding display counter unit, a return pipe 31 or the like being provided for leading the brine back to the tank 10.

In Figs. 3, 4 and 5 are shown various modifications of the arrangement previously described. In Fig. 3 is shown an arrangement wherein the header pipe 25^a is located at one end of the shelf 18^a which is, in this instance, arranged to afford spaces at its ends for the circulation of air currents in the manner indicated by the arrows. Fig. 4 shows a second modification in which two headers 25^b are located near the center of the display compartment and discharge in opposite directions towards the ends thereof beneath the shelf sections 18^b which are spaced apart in the center to permit of the establishment of two oppositely directed air currents. Fig. 5 shows a modification of the above in which the header pipes 25^c are located near the ends of the display compartment and direct jets of liquid toward the center thereof beneath the shelf sections 18^c. Other modifications of the same general idea might be made without departing from the spirit of the invention.

Furthermore, the brine tank might, if desired, be located at a distance from the compartment or compartments to be cooled and the brine or other cooling medium discharged through a suitable system of pipes adapted to the requirements of local conditions. The cooling medium employed may be any suitable liquid mixture, such as is commonly employed for refrigerating purposes, such, for instance, as ice and water, ice and salt and water; or in cases where cooling coils are available, the same may be housed within the tank and utilized to reduce the temperature of the refrigerant employed, so that it will be understood that the term "brine tank" is intended to cover a tank intended to house the liquid cooling mixture whatever may be the constituents thereof.

In order to prevent the ingress of solid particles which might tend to clog the system, it is preferred to provide a screen 31 over

the end of the pump intake 23. The spray system of the present invention is peculiarly adapted to the requirements of a display counter in that it does not encumber any portion of the structure devoted to the display of the goods and permits ready access to be obtained thereto from the rear.

This method of refrigeration does away with the use of refrigerants placed behind the counter, as is commonly the case, which method of cooling makes it necessary for the attendant to reach over the refrigerating chamber of the counter to gain access and to handle the goods on display, and it also does away with the necessity for placing a refrigerating compartment at each end of the counter or in the center thereof, which method of refrigeration is extremely wasteful of space and frequently reduces the space available for display purposes by at least 20%.

By the use of the spray system, acting under the pressure of the pump, the natural tendency of the cool air to fall is overcome, and currents of cool air are caused to rise to the top of the counter, so that it is thereby possible to reverse the usual arrangement observed in the construction of refrigerators, and to locate the cooling medium below, rather than above, the storage or display compartment.

The arrangement is one which enables the counters to be arranged in unit order, since one of the counters may be equipped to serve as a master counter from which the brine is distributed to the other counters composing the series, although obviously each counter section may be in the form of a self-contained unit fully equipped with a brine tank and motor to operate independently of other units.

I claim:

1. In a refrigerated display counter, the combination of a structure provided with a substantially horizontally disposed partition wall dividing the structure into an upper display compartment and a lower brine compartment, a brine cooling tank in the lower compartment and in communication through a drainage opening in the partition with the upper compartment, a shelf within the display compartment elevated slightly above the partition, to afford a relatively broad and low spraying space, the shelf having along its opposite edges passageways for the upflow and return downflow of air respectively to and from the display portion of the display compartment, a spray pipe located beneath the shelf and at a point adjacent to the return downflow air passage and provided on the side fronting the spraying space with discharge openings directed toward said space and adapted to direct the flow of jets of cooling liquid in a substantially horizontal plane beneath the

shelf and in substantial parallelism therewith to create air currents through the relatively narrow spraying space beneath the shelf, and upwardly through the air passage toward which the jets are directed, and to cause said air currents to return downwardly through the air passage adjacent to the spray pipe, a pump communicating with the brine tank and the spray pipe, and means for driving said pump, substantially as described.

2. In a refrigerated display counter, the combination of a structure provided with a substantially horizontally disposed partition wall dividing the structure into an upper display compartment and a lower brine compartment, a brine cooling tank in the lower compartment and in communication through a drainage opening in the partition with the upper compartment to receive drainage therefrom, a shelf within the display compartment elevated slightly above the partition to afford a relatively broad and low spraying space, the shelf having along its opposite edges passageways for the upflow and downflow of air respectively to and from the display portion of the display compartment, a spray pipe located beneath the shelf and at a point adjacent to the return downflow air passage and provided on the side fronting the spraying space with discharge openings directed toward said space and adapted to direct the flow of jets of cooling liquid in a substantially horizontal plane beneath the shelf and in substantial parallelism therewith to create air currents through the relatively narrow spraying space beneath the shelf and upwardly through the air passage toward which the jets are directed and to cause said air currents to return downwardly through the air passage adjacent to the spray pipe, a pump communicating with the brine tank and the spray pipe, means for driving said pump, and means in communication with the pump and leading to a point outside of the structure for serving a second display counter unit from the same pump, substantially as described.

3. In a refrigerated counter, a compartment provided near its base with a substantially horizontal shelf dividing the compartment into a relatively high and large overlying space for the housing of perishable articles and a relatively low broad underlying spraying space, the shelf having along its opposite edges passageways for the upflow and return downflow of air respectively to and from the overlying housing space, a spray pipe located beneath the shelf and provided on the side fronting the spraying space with discharge openings directed toward said space and adapted to direct the flow of jets of cooling liquid in a substantially horizontal plane beneath the

shelf and in substantial parallelism therewith to induce air currents through the relatively narrow spraying space beneath the shelf and upwardly through the air passage toward which the jets are directed and to cause said air currents to return through the downflow air passage, the base of the compartment being provided with a drain passage, a brine cooling tank in communication with said drain passage, and a pump in communication on its intake side with the brine tank and on its discharge side with the spray pipe, and means for operating the pump, substantially as described.

4. In a refrigerated counter, a compartment provided near its base with a substantially horizontal shelf dividing the compartment into a relatively high and large overlying space for the housing of perishable articles and a relatively low broad underlying spraying space, the shelf being spaced along opposite edges from the proximate walls of the compartment to afford passageways for the upflow and return downflow of air respectively to and from the overlying housing space, a spray pipe located beneath the shelf and at a point adjacent to and substantially parallel with the edge of the shelf proximate to the return downflow passage and provided on the side fronting the spraying space with discharge openings directed toward said space and adapted to direct the flow of jets of cooling liquid in a substantially horizontal plane beneath the shelf and in substantial parallelism therewith to induce air currents through the relatively narrow spraying space beneath the shelf and upwardly through the air passage toward which the jets are directed and to cause said air currents to return downwardly through the air passage adjacent the spray pipe, the base of the compartment being sloped downwardly from the spray pipe and provided near its distant edge with a drain passage, a brine cooling tank in communication with said drain passage, and a pump in communication on its intake side with the brine tank and on its discharge side with the spray pipe, and means for operating the pump, substantially as described.

5. In a refrigerated counter, a structure having means for dividing it into a relatively high and capacious display compartment for the housing of perishable articles, and a relatively low and restricted underlying spraying space, said spraying space being in communication at each end with the overlying display compartment through air upflow and downflow passages respectively, a spraying pipe adapted to discharge into the spraying space and located in proximity to the downflow air passage, and provided on the side fronting the spraying space with a discharge opening toward said space adapted to direct the flow of a jet of

cooling liquid beneath the base of the display compartment to induce air currents through the relatively restricted spraying space and upwardly through the air upflow 5 passage toward which the jet is directed and to cause said air currents to return through the downflow air passage, the base of the spraying space being provided with a drain

passage, a brine cooling tank in communication with said drain passage, and a pump 10 in communication on its intake side with the brine tank and on its discharge side with the spray pipe, and means for operating the pump, substantially as described.

JOSEPH BLAZEK.
